UNITED STATES PATENT OFFICE.

PETER LOSSELYOUNG, OF STAUNTON, VIRGINIA.

DEVICE FOR PROTECTING BANK OFFICIALS.

1,288,070.

Specification of Letters Patent.

Patented Dec. 17, 1918.

Application filed June 2, 1916. Serial No. 101,349.

To all whom it may concern:

Be it known that I, PETER LOSSELYOUNG, a citizen of the United States, residing at Staunton, in the county of Augusta, State of Virginia, have invented certain new and useful Improvements in Devices for Protecting Bank Officials; and I do hereby declare the following to be a full, clear, and exact description of the invention, such as will enable others skilled in the art to which it appertains to make and use the same.

The present invention is directed to improvements in devices for protecting bank officials from robbers, and has for its object 15 to so construct a device of this character that the teller can upon simply pulling a cord close the windows of the cage and simultaneously the door to the bank.

A further object of the invention is to provide a device of this character so constructed that the teller can simultaneously close the windows of the cage and entrance door should a robber enter the bank, thereby trapping the robber in the bank until assistance can be obtained.

With these and other objects in view, this invention resides in the novel features of construction, formation, combination and arrangement of parts to be hereinafter more fully described, claimed and illustrated in the accompanying drawing, in which:—

Figure 1 is a fragmentary plan view of the device.

Fig. 2 is a sectional view on line 2—2 of Fig. 1.

Fig. 3 is a sectional view on line 3—3 of Fig. 1.

Fig. 4 is a sectional view on line 4—4 of Fig. 1.

Fig. 5 is a sectional view on line 5—5 of Fig. 1.

Fig. 6 is a sectional view on line 6—6 of Fig. 5.

Referring to the drawing 1 indicates the teller's desk, and 2 the window frame of the teller's cage. The frame 2 is also provided with a doorway 3 so that a person can pass from the lobby of the banking room 4 to the teller's cage.

50 Slidably associated with the frame 2 are

closures 5, and a door 6. The upper edge of the closures 5 are connected to one end of the beam 8 by a coil spring 9.

Slidably associated with the entrance door 10 of the bank is a door 11, said door having 55 its upper end provided with a flange 12 which slides on the beam 13. This flange is connected to the wall of the bank by a coil spring 14.

Fixed beneath the desk 1 is a drum 15 60 which has secured thereto the cords 16 and 17 which have their other ends connected to the closures 5 and door 11, respectively.

The drum 15 has associated therewith a ratchet wheel 18, and normally engaged 65 with this wheel is a spring pressed pawl 19. A cord 20 is provided and is passed through the opening 21 in the desk 1 and has its lower end connected to the pawl 19, while the upper end of said cord is in convenient 70 reach of the teller.

The drum is provided with a shaft 22 which has its outer end squared for engaging the socket of the crank handle 23, said handle being used to rotate the drum 15 so 75 that the cord 16 and 17 will wind thereon, thereby holding the closures 5 and door 11 open, and at which time the springs 9 and 14 are expanded.

Should a robber enter the room 4 and attempt to hold up the teller, the teller can upon pulling on the cord 20 actuate the pawl 19 so that it will disengage the ratchet wheel 18, whereupon the springs 9 and 14 will contract, thereby simultaneously closing the 85 door 11 and closures 5 so as to protect the teller and trap the robber.

While the device is particularly adapted for protecting bank officials it is obvious that the same can, with minor changes be 90 used in connection with locomotive cabs and express cars.

What is claimed is:—

A device of the class described comprising a window frame and a door frame arranged 95 at right angles to each other, horizontal beams disposed above each of said frames, closures for said frames slidably longitudinally of said beams and at right angles with respect to each other, a winding drum. 100

cords having certain ends connected with said closures and the other ends with said drum, pulleys around which said cords engage, a pawl associated with said drum for locking it, springs connected to and extending longitudinally of said closure and beams and tensioned by the winding of cords upon said drum whereby to simultaneously close said closures when the pawl

is released, and a flexible member connected 10 to said pawl for releasing the same.

In testimony whereof, I affix my signature, in the presence of two witnesses.

PETER LOSSELYOUNG.
